US00D980629S

(12) **United States Design Patent** (10) **Patent No.:** **US D980,629 S**
(45) **Date of Patent:** **** Mar. 14, 2023**

(54) **CASE**

(71) Applicant: **Apple Inc.**, Cupertino, CA (US)

(72) Inventors: **Jody Akana**, Los Altos Hills, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Daniel J. Coster**, San Francisco, CA (US); **Daniele De Iuliis**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Joe Sung-Ho Tan**, Vienna (AT); **Clement Tissandier**, San Francisco, CA (US); **Eugene Antony Whang**, San Francisco, CA (US); **Rico Zörkendorfer**, San Francisco, CA (US)

(73) Assignee: **Apple Inc.**, Cupertino, CA (US)

(**) Term: **15 Years**

(21) Appl. No.: **29/849,506**

(22) Filed: **Aug. 11, 2022**

Related U.S. Application Data

(63) Continuation of application No. 29/752,516, filed on Sep. 28, 2020, now Pat. No. Des. 960,829, which is

a continuation of application No. 29/726,068, filed on Feb. 28, 2020, now Pat. No. Des. 897,291, which is a continuation of application No. 29/692,476, filed on May 24, 2019, now Pat. No. Des. 878,045, which is a continuation of application No. 29/594,338, filed on Feb. 17, 2017, now Pat. No. Des. 849,401, which is a continuation of application No. 29/576,707, filed on Sep. 6, 2016, now Pat. No. Des. 806,388.

CLAIM

The ornamental design for a case, as shown and described.

DESCRIPTION

FIG. 1 is a top front perspective view of a case showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view thereof taken along line 8-8 in FIG. 6; and,

FIG. 9 is a top front perspective view thereof in an environment in which it may be used.

The broken lines in the figures show portions of the case and environment that form no part of the claimed design.
The cross-hatching in FIG. 8 forms no part of the claimed design.
